UNITED STATES PATENT OFFICE.

BERNARD SHELDON, OF BROOKLYN, NEW YORK.

MACHINE FOR CUTTING AND STAMPING CIGARS.

SPECIFICATION forming part of Letters Patent No. 597,593, dated January 18, 1898.

Application filed March 11, 1897. Serial No. 627,006. (No model.)

To all whom it may concern:

Be it known that I, BERNARD SHELDON, of Brooklyn, in the county of Kings and State of New York, have invented a new and Improved 5 Machine for Cutting and Stamping Cigars, of which the following is a full, clear, and exact description.

The object of my invention is to provide a machine in which will be combined a device 10 for cutting the ends off cigars and a device for bringing type in a position to print upon or stamp a cigar.

A further object of the invention is to so connect the cutting mechanism with the stamping mechanism that the latter will be brought 15 into operation when the former is carried to the position to cut or trim the cigar.

Another object of the invention is to provide a clamp through the medium of which 20 the cigar to be cut and stamped may be firmly held upon a table, but engaged in such manner that the cigar will receive no injury.

Another object of the invention is to construct the various parts in a simple, durable, 25 and economic manner, and to provide a covering for the opening in the table through which the type extends when stamping a cigar, the said covering being automatically carried over the opening when the clamp is 30 released, thereby preventing any trimmings from the cigar from falling on the face of the stamp or type.

The invention consists in the novel construction and combination of the several 35 parts, as will be hereinafter fully set forth, and pointed out in the claims.

Reference is to be had to the accompanying drawings, forming a part of this specification, in which similar characters of reference indicate 40 corresponding parts in all the figures.

Figure 1 is a plan view of the machine. Fig. 2 is a side elevation thereof. Fig. 3 is a transverse section taken substantially on the line 3-3 of Fig. 1, the parts of the machine being 45 in their normal position; and Fig. 4 is a view similar to Fig. 3, illustrating the cutter and the stamping device both as brought into operation.

The frame A of the machine comprises a 50 table 10, a side 11, projected downward from the table, and two end pieces 12, the side being provided, preferably, with lugs 13, extend-

ing below its lower edge to engage with the side surface of a support upon which the frame rests, as shown in Figs. 2 and 4.

A groove 14 is made longitudinally in the top of the table, preferably adjacent to the uncovered side of the frame, the said groove being adapted to receive a cigar. At one end of the groove a slot 15 is made in the table, 60 the slot being virtually a continuation of the groove, as that portion of the cigar to be printed upon is made to extend over this slot. A clamp 16 is supported over the slot 15, the under face of the clamp being preferably concaved and its upper face convexed. An arm 17 is secured to the central portion of the clamp 16, which arm is carried in direction of the closed end of the frame and is fulcrumed upon bearings 18, secured to the table. 65 At the rear of the bearings 18 a slot 20 is produced in the table, through which a link 19 is carried downward, the upper end of the link being pivotally attached to the rear end of the arm 17, attached to the clamp, since 70 the open portion of the frame is virtually its forward side. The link 19 is provided with a longitudinal slot 19^a, as shown in Figs. 3 and 4, and at the rear upper portion of the link a lug 21 is projected outward and normally rests upon the table, as shown in Fig. 3, when the clamp is not being used, the clamp being at that time held in an elevated position, also shown in Fig. 3, by means of a spring 22, secured to the frame A and to the 75 lug 21 of the link. A bar 23, located beneath the table, is pivoted at its inner end in the slot 19^a of the link 19. The bar 23 is attached to a cover-slide 24. This slide is supported at its ends in ways 25, made at the ends of the 80 slot 15, and when the clamp 16 is in its elevated position or is not in use the cover-slide 24 will be beneath the opening 15, completely closing it, as shown in Fig. 3, so that scraps of material cannot drop downward through 85 said opening.

The object of closing the opening 15 when the machine is not in use is to prevent the scraps from falling upon the type, since immediately below the opening 15 a type-bed 26 is horizontally supported, the said bed being usually in the nature of a bar. The bed loosely receives studs 27 at its ends, the said studs being projected downward from the un-

der face of the bed, as shown particularly in Fig. 2. The type 28, placed in a form 29 or otherwise held together, is secured in any suitable or approved manner on the type-bed 26, and a lamp 29^a of any desired construction is located beneath the type-bed in order that the type shall be kept warm.

The fixed member 30 of a cigar-cutter of ordinary type is secured to one end of the table, its curved or cutting edge being at the end of the groove 14 for the cigar, and the movable jaw or member 31 of the cutter is provided with the ordinary curved cutting edge to coöperate with the corresponding edge of the fixed jaw of the cutter, as shown in Figs. 3 and 4. The pivoted jaw 31 is normally held elevated by means of a spring 32, attached to it and to the frame, the said spring being compressed when the pivoted jaw is carried 20 downward. A link 33 is pivotally attached to the movable jaw 31 of the cutter, extending downward through an opening 34 in the table. The lower end of the link is pivoted to the short end of a lever 35, which lever is fulcrumed upon an end piece 12 of the frame. A lift-bar 36 is attached to the lower and longer end of the lever, extending upward at an angle thereto, being provided at the top with a head 37, which is at an angle to the lift-bar. The head 37, when the parts of the machine are inactive, is below the type-bed and out of engagement therewith; but when the pivoted jaw of the keeper is carried downward the lift-bar is carried upward, engaging 30 with the under face of the type-bar, and at the time the pivoted jaw of the cutter is brought into cutting action with its fixed jaw the type carried by the type-bed will have been pushed upward a sufficient distance to 40 bring the type in engagement with the cigar. Just before operating the cutter, however, the clamp 16 is engaged ordinarily by the fore and middle fingers of the hand, one being placed at each side of the arm 17. Upon pressing the clamp downward to an engagement with the cigar the cover-slide 24 is carried rearward, as shown in Fig. 4, permitting the type to ascend when the cutter is operated. A clamp shaped and operated as described 45 will hold the cigar firmly on the table in position to be cut and stamped without injury to said cigar.

I desire it to be understood that preferably the stationary member or jaw 30 of the cigar-cutter is made adjustable upon the frame, as shown in dotted lines in Figs. 3 and 4—namely, by making the slots in the lower portion of said member or jaw and passing screws through the slots into the frame. I desire it 50 to be further understood that a drawer may be placed in the frame, as shown in dotted lines in Fig. 2, to hold the type not in use.

Having thus described my invention, I claim as new and desire to secure by Letters 55 Patent—

1. The combination of the support having an opening, the type-bed below said opening,

the movable clamp above the opening, means for operating the type-bed, and a slide operated from the clamp and adapted to cover and uncover the opening in the support, substantially as described.

2. The combination of the support having an opening, the type-bed below said opening, the slide adapted to cover and uncover said opening, and means for operating the slide, substantially as described.

3. The combination, with a support for a cigar, a cigar-cutter and a type-bed operated from the cigar-cutter, the said support being provided with an opening in the surface prepared to receive the cigar, of a movable clamp adapted for engagement with the cigar above its support, and a slide for the bottom portion of the opening in said support, said slide being operated by the movement of the clamp, as and for the purpose specified.

4. In a machine for stamping cigars, a table having an opening in its surface prepared for the reception of a cigar, a movable clamp located above the table and arranged for engagement with a cigar placed over said opening, a slide operated from the clamp, being adapted to cover and uncover the bottom portion of the opening in the said table, a type-bed located below the said opening in the table, and means for operating the said type-bed, as and for the purpose specified.

5. In a machine for cutting and stamping cigars, a table having an opening in the surface prepared to receive the cigar, a cigar-cutter connected with the table, a type-bed loosely supported beneath the table, capable of movement to and from the opening therein, a device for operating the type-bed through the movement of the pivoted jaw of the cutter, a slide normally located beneath the opening in the table and above the type-bed, a clamp fulcrumed above the table, comprising a head or body and an arm, the head or body being located over the opening in the table, a link connection between the slide and the arm of the clamp, and a tension device normally holding the head or body of the clamp elevated and the slide under the opening in said table, as and for the purpose set forth.

6. In a machine for stamping cigars, a table having an opening therein over which the cigar is to be placed, a movable type-bed under the table, means for operating the type-bed, a clamp fulcrumed above the table, comprising an arm and a head or body, the latter extending longitudinally over the opening in the table, a slide connected with and operated from the clamp, the slide being normally located under the opening in the table, and a tension device likewise connected with the clamp, normally holding the head thereof at a predetermined elevation above the table, as and for the purpose specified.
